Attorney

UNITED STATES PATENT OFFICE.

LOUDON E. MACFADYEN, OF PHILADELPHIA, PENNSYLVANIA, ASSIGNOR TO TAYLOR-WHARTON IRON AND STEEL COMPANY, OF HIGH BRIDGE, NEW JERSEY, A CORPORATION OF NEW JERSEY.

DRAG-CONVEYING CHAIN.

Application filed October 6, 1925. Serial No. 60,792.

My invention relates to conveyers of the dragline type and particularly to such as find their chief utility in cement mills and other places where material is handled in bulk. Conveyers of this type comprise pivotal links operating as a strand in a trough or way and equipped with a drop pan or bottom closure adapted and arranged for selective operation to deliver the load at desired points along the route. The units suffer heavy abrasive wear and shock and have to be replaced after comparatively short service.

The object of my invention is to simply the construction of the units whereby they may be integrally constructed of shock and wear resisting material such as, for example, manganese steel.

The nature, characteristic features and scope of the invention will more readily be understood from the following description taken in connection with the accompanying drawing, forming a part hereof, wherein—

Figure 1 is a plan view of a section of conveying chain embodying my improvements.

Figure 2 is a side elevational view, partly in section, of the same.

According to my invention the chain units are preferably constructed of manganese steel. They may, however, be constructed of other metal capable of producing sound sturdy castings. But manganese steel notwithstanding its greater initial cost is more economical because of its greater service factor.

The chain units are integrally formed with side bars 5 joined by transverse bars 6 and 7. The side bars have bottom edge marginal offsets or drag flanges 8 and stiffening ribs 9. The chain units are longitudinally inclined, as usual, to provide for linkage connection of mated ends of adjoining units. For this purpose the side bars 5 have cored openings 10 for the reception of a pintle 11, which passes through and provides hinge connection for the transverse bar 7 of the adjoining chain unit.

The transverse bars 7 are of reinforced construction to provide for depending lugs 12 formed with eyes, or hollow bosses 13 for the reception of a pintle 14 which hingedly connects the drop pan or bottom closure 15. The latter by preference is also constructed of manganese steel and has a reinforced front or lip 16.

As is well understood by those familiar with the handling of clinker and other material in bulk, the chain is operated in a trough 17. The trough is ordinarily equipped with a slide (not shown) which can be manipulated to expose openings 18 and permit the swinging pan or floor plate to drop and discharge its load at desired points.

Having described my invention, I claim.

1. A dragline or chain conveyer whereof the units are of mated construction of the integral type and are joined by linkage provisions, said units consisting of side bars and transverse bars, the side bars having bottom edge marginal offsets and stiffening ribs, and the transverse bars having integral linkage provisions for swinging floor plates, and floor plates operatively connected therewith.

2. A conveyer of the linkage type whereof the units are integrally constructed of manganese steel and reinforced for the carriage of swinging floor plates, said units having depending lugs with aligned hollow bosses, a manganese steel floor plate having hollow bosses which mate with the first mentioned bosses, and a pintle connecting the two sets of bosses.

3. A unit for conveyers of the linkage type, embodying a chain link of the integral construction type formed with depending lugs having hollow bosses, a floor plate having a reinforced front or lip and hollow bosses, and a pintle connecting the two sets of bosses.

In testimony whereof I affix my signature.

LOUDON E. MACFADYEN.
